(57) CLAIM

The ornamental design for a videophone, as shown and described.

DESCRIPTION

FIG. 1 is a front perspective view of a videophone in accordance with the present invention;

FIG. 2 is a front view thereof;

FIG. 3 is a right side view thereof;

FIG. 4 is a right side view thereof with the cover open;

FIG. 5 is a front perspective view thereof with the cover open;

FIG. 6 is a bottom right perspective view thereof with the cover open; and,

FIG. 7 is a front view thereof with the cover open.

The broken line showing of environmental structures in FIGS. 1, 5, and 6 is for illustrative purposes only and forms no part of the claimed design.
